UNITED STATES PATENT OFFICE.

FERDINAND C. ROBERTS, OF DETROIT, MICHIGAN.

SIGNAL FOR AUTOMOBILES.

1,354,066.

Specification of Letters Patent. Patented Sept. 28, 1920.

Application filed October 16, 1916. Serial No. 125,793.

To all whom it may concern:

Be it known that I, FERDINAND C. ROBERTS, a citizen of the United States of America, residing at Detroit, in the county of Wayne 5 and State of Michigan, have invented certain new and useful Improvements in Signals for Automobiles, of which the following is a specification, reference being had therein to the accompanying drawings.

10 This invention relates to a signal for automobiles and to an arrangement thereof whereby the desired warnings are easily seen and whereby the license plate is likewise illuminated, all with an expenditure of a 15 minimum amount of electric energy.

The invention consists in the matters hereinafter set forth, and more particularly pointed out in the appended claims.

In the drawings,

20 Figure 1 is a view partially in longitudinal section and partially broken away and in elevation, of a device embodying features of the invention;

25 Fig. 2 is a view in transverse section there- through;

Fig. 3 is a diagrammatic view of the electric connections; and

Fig. 4 is a view in perspective of the device, on reduced scale.

30 As herein shown in preferred form a substantially rectangular main casing 1 has a longitudinal upright wall 2 therethrough which is extended forwardly as at 3, to form a signal box interior which is illuminated by

35 a bulb 4 mounted appropriately on the wall 2. An opening over which there is a plate 5 of transparent material, such as glass or the like, is formed in the bottom of the main casing back of the partition 2 in such

40 way that a bulb 6 that is mounted on the back wall 7 of the casing may throw light therethrough and thus illuminate any license plate 8 that may be secured as by screws and slots 9 in a depending rear wall 10. An

45 arched hood 11 over the top of the casing houses the bulb 6 and the interior thereof is preferably burnished or polished to act as a reflector. A bull's eye 12 or the like is mounted in the front wall 13 of the hood,

50 said wall being an extension of the front of the casing and being hinged as at 14, to permit the inspection of the interior. A suitably lettered translucent or transparent plate 15 forms the lower panel of the casing

55 door in front of the bulb 4, the indicia thereon being such as to be visible by re-

flected light in the day time and by transmitted light at night. A suitable bracket 16 on the rear wall permits the mounting of the casing in the usual position of a tail 60 light.

The source of electrical energy indicated diagrammatically in Fig. 3 at 17, being in the usual ignition system or like system used on vehicles, is connected in series through 65 the leads 18 to the lamps 6 and 4. A switch 19 near the operator's station on the vehicle is connected through a shunt line 20 with the leads 18 so that when the switch 19 is closed, the resulting shunt therethrough causes the 70 lamp 4 to glow and cuts off the tail light 6. The voltage of the tail light 6 is so proportioned in relation to that of the lamp 4, that in normally operating conditions, with the switch 19 open, the tail lamp 6 glows and 75 the lamp 4 does not. A permanent cut out switch 21 throws the lamp 6 out of commission in the daylight.

As a result of this construction, a very efficient, easily operated and simple signal is 80 obtained which performs the usual function of a tail light, a traffic signal, and an illuminating lamp for the license plate. Ordinarily the voltage of the tail light and intermittent use of the higher voltage lamp is 85 no serious drain upon the source of energy, which if it is a storage battery, should not have any continuous drain of any appreciable amount upon it.

Obviously, changes in the details of construction may be made without departing from the spirit of my invention and I do not care to limit myself to any particular form or arrangement of parts.

What I claim is:—

1. In tail light construction wherein a pair of lamps are supported to illuminate two independent warning signals and a license number plate, means for supporting the elements in relative positions, said means including a casing having a body portion having a partition to divide the body portion into two compartments arranged in front and rear relation, the vertical portion of the partition carrying one of such lamps located in the front compartment in rear of one of the signals, a hood overlying both compartments and in open communication with the rear compartment, said hood carrying the second signal, a lamp for the second signal supported by the rear wall of the casing and positioned above said rear compartment.

ment and within the hood, said second compartment having a bottom adapted to permit passage of light rays therethrough, a license number plate supported by the rear 5 wall of the casing to position it in rear of such light rays, and lamp connections located within the rear compartment, the lamps and connections being so disposed as to permit substantially unobstructed passage 10 of light rays from the second lamp to said compartment bottom.

2. Construction of the type of claim 1, characterized by means for controlling the activity of the lamps at will, said means including a pair of make and break devices 15

within the circuit connections and operative to control the activity of the lamps individually, said circuit connections and lamp construction being operative to prevent concurrent illuminating of signals, one of said 20 devices being operative by its make and break action to select the signal to be illuminated when the other device is in circuit closing position.

In testimony whereof I affix my signature 25 in presence of two witnesses.

FERDINAND C. ROBERTS.
